PUTTER

H. Douglas Wilmoth, Lakewood, Colo., assignor to The Lange Company, Broomfield, Colo.

Filed Nov. 19, 1971, Ser. No. 200,667

Term of patent 14 years

Int. Cl. D21—02

U.S. Cl. D34—5 CB

FIG. 1 is a perspective view of the putter showing my new design;

FIG. 2 is a front elevation;

FIG. 3 is a rear elevation;

FIG. 4 is a top plan;

FIG. 5 is a bottom view; and

FIG. 6 is a side view.

The shaft is shown fragmentarily for convenience of illustration in FIGS. 2 through 6.

I claim:

The ornamental design for a putter, as shown and described.
